John Stewart.

UNITED STATES PATENT OFFICE

WILLIAM HARRIS, OF PATERSON, NEW JERSEY

LOOM

Application filed February 9, 1931. Serial No. 514,578.

This invention relates to ribbon looms of the class represented by my Patent No. 950,021, in which the rotary device forming the supply of warp for each ribbon and the rotary device for receiving such ribbon are so connected that the latter is driven from the former, whereby the ribbon will be wound on the receiving device as the warp is unwound from the supply device.

10 The principal object of the invention is to attain an appreciable economy of floor space in the use of looms of this class and at the same time have all the devices within easy reach of the weaver for his attention from

15 time to time.

In the present practice with the use of looms of this type if it is desired to double the length of the warp used it is the custom to wind one-half of the double-length warp on each of two spools or equivalent devices (thus filling each to capacity) and then place these two, interlocked to rotate together, in alignment with each other and the corresponding ribbon-receiving device, or all on the same spindle; again, if the ribbon required 20 selvage it was the custom to wind the selvage warps on a separate spool or equivalent device and place this spool, interlocked with the body warp spool for rotation therewith, in alignment with such body warp spool, or with the receiving device and body and selvage warp spools all on the same spindle. In either case this meant serious encroachment on valuable floor space.

30 According to my invention, if the warp is to be doubled in length, or if a selvage warp is required, the supplemental spools or equivalent devices for such supplemental warps are placed at the front of the "castle" or superstructure of the loom, whereby floor space is saved and they are easily within reach of the weaver for his attention.

In the drawings,

40 Fig. 1 is a front-to-rear section of a loom embodying the invention; and

Fig. 2 shows one of the supplemental supply devices and its braking means in side elevation.

1 is the loom frame; 2 the breast-beam carrying the glass-bars 3; 4 the suspended lay or batten structure; 5 the harness; and 6 the usual beam supporting glass-bars 7.

50 The warp 8 for each fabric extends from a supply spool or equivalent device 9 over guides, as rollers, 10 journaled in the superstructure or castle 11 of the frame, a suspended loop 12 being formed in the warp between some of said rollers and sustaining a weight or weights 13; from the rollers this warp extends under the glass-bars 7 forward 55 through the harness and over the batten. The ribbon 14 extends over the glass-bar 3, around the sand-rollers 15, over the pressure roller 16, back under the guide-bar 17 and up to the receiving spool or core 18. Each 60 two devices 9 and 18 are journaled on a single spindle 19 of the "castle" or superstructure, and they are separably intercoupled, as in my said patent, so that they rotate as one, wherefore the rotation of the core 9 under 65 the pull of the warp as the weaving proceeds rotates core 18 in the same direction, the ribbon 14 being wound on the core 18 as the warp unwinds from core 9. All this is the same as in my said patent.

70 At the front of the castle there are spindles, as 20, projecting forwardly. On each of these is revoluble a spool or other supply device 21 for the supplemental warp for 75 each ribbon, and this has coupled to rotate 80 therewith a flanged sheave or pulley 22, such coupling here comprising studs 23 and 24 on the spool and sheave. The supplemental warp 25 for each ribbon 14 extends from the mass on the spool 21 up over a roller 26 on the castle, then back under one and forward over another of the rollers 10, then down between the latter roller and a third roller 10 85 in a bend or loop 27 sustaining a tension weight 28, then down under glass-bars 7, 90

where it assumes the plane of the warp 8 and becomes thereupon woven into the ribbon 14. Attached at one end to a stud 29 on the castle is a flexible connection 30 which is given one or more turns around the sheave and has its other end attached to a weight 31, thus acting as a brake-member. Connecting the weights 28 and 31 is a wire or other link 32.

- 10 The operation of the improved loom, so far as the system comprising the ribbon and body warp 8 is concerned, is the same as in my said patent excepting that the supplemental warp is derived from a supply independent of the devices 9 and 18, and has its own tension let-off means; that is to say, the brake member 30 holds the core 21 fast until the loop 27 has in the weaving been taken up sufficiently to act through link 32 to relax the braking action, whereupon the brake lets go, the weight 28 draws off warp from said core by causing rotation thereof, with consequent re-extension of the loop and re-setting of the braking action on said core.
- 15 20 25 It will be noted that my arrangement avails itself of the same guides 10 for the selvage warps that are used for the body warp, so that additional guides are avoided and the selvage warps and body warp extend, as heretofore, substantially together down to the glass-bars 7.

Having thus fully described my invention what I claim is:

1. In a loom, the combination of the frame 35 having a superstructure, a rotary fabric receiving device and a warp supply device connected to rotate together whereby to wind the fabric on said receiving device as the warp is unwound from said supply device, 40 said devices being supported on and at the back of said superstructure, means to tension the band formed by the warp and fabric, a supplemental warp supply device on which a supplemental warp is wound rotative independently of the first two devices and supported on and at the front of the superstructure, and means to tension the supplemental warp independently of said band, said frame having means to guide the fabric 45 and both warps.

2. In a loom, the combination of the frame having a superstructure including spaced guides, a rotary fabric receiving device and a warp supply device connected to rotate together whereby to wind the fabric on said receiving device as the warp is unwound from said supply device, said devices being supported at the back of said superstructure and the warp extending over two of said 55 guides, means to tension the band formed by the warp and fabric and engaging the warp between said guides and maintaining a loop therein, a supplemental warp supply device on which a supplemental warp is wound rotative independently of the first 60

two devices and supported on and at the front of said superstructure, said supplemental warp extending from said supplemental supply device over two of said guides and to the fabric, means to tension the supplemental warp engaging the same between the guides engaged thereby and maintaining a bend therein, and means, controlled by said bend, for controlling the rotation of the supplemental supply device, said frame having 70 means, coactive with the first two guides, to guide the fabric and both warps.

In testimony whereof I affix my signature.

WILLIAM HARRIS.
